(57) **CLAIM**

The ornamental design for a jewelry article, as shown and described.

DESCRIPTION

FIG. 1 is a front, top, perspective view of a first embodiment of a jewelry article showing my new design;
FIG. 2 is rear bottom perspective view thereof;
FIG. 3 is a front elevation view thereof;
FIG. 4 is rear elevation view thereof;
FIG. 5 is a side view thereof;
FIG. 6 is a top view thereof; and,
FIG. 7 is a bottom view thereof.

The broken lines shown immediately adjacent to the shaded areas represent a boundary of the claimed subject matter. The other broken lines illustrate environmental subject matter only and form no part of the claimed design.
